UNITED STATES PATENT OFFICE.

OLEF JOHNSON, OF HUDSON, WISCONSIN.

RAIL-JOINT.

1,103,881.

Specification of Letters Patent. Patented July 14, 1914.

Application filed January 5, 1914. Serial No. 810,465.

To all whom it may concern:

Be it known that I, OLOF JOHNSON, a subject of the King of Sweden, and a resident of the city of Hudson, county of St. Croix, 5 and State of Wisconsin, have invented certain new and useful Improvements in Rail-Joints, of which the following is a specification.

My invention relates to improvements in 10 rail joints and has for its object the production of a rail joint which will be so constructed as to permit of relative longitudinal movement of the abutting rails in order to allow for expansion or contraction such 15 as occurs during changes in temperature.

A further object is the production of a 20 rail joint which will prevent sagging at the abutting ends of the rails and thereby obviate the jolting and pounding of railway cars such as is incidental to the sagging of 25 the rail ends as mentioned.

A still further object is the production of a rail joint which generally will be strong and durable and of economical construction.

Other objects will appear hereinafter.

The invention consists in the combinations and arrangements of parts hereinafter described and claimed.

The invention will be best understood by 30 reference to the accompanying drawing forming a part of this specification, and in which—

Figure 1 is a perspective view of a rail joint embodying my invention, Fig. 2 is an 35 enlarged transverse section taken on substantially line $x-x$ of Fig. 1, Fig. 3 is a side elevation partly in section of one of the rail ends, the sectional portion illustrating the connection between the rail and the chair 40 in which the same is mounted, Fig. 4 is a top plan view of the rail end shown in Fig. 3, and Fig. 5 is a perspective view of the key and cotter pin which cooperates therewith in loosely connecting one of the rail 45 ends with the chair of the device.

The preferred form of construction as 50 illustrated in the drawing comprises a pair of abutting rails 1 and 2, the outer ends of said rails being of the usual form and design, the same being provided with spaced 55 openings as shown in order to permit of the connection thereof with the usual rail sections in the construction of a railway track.

The inner or abutting ends of the rails 1 and 55 2 are beveled or tapered as at 3 and overlapped, this construction, when the rail joint

is in use, eliminating the break in the tread of a rail which results where the abutting ends of the rails are disposed at right angles to the length of the rail. Said ends of said rails are of increased thickness as shown in order to reinforce the same and thereby prevent sagging. To further prevent sagging the abutting rail ends are mounted in a snugly fitting chair 4, the latter being of channel form in cross section and designed to snugly embrace the base of said rail ends, the sides or upwardly extending flanges 5 and 6 of said chair fitting closely against the sides of said rails as clearly shown in Fig. 2. At the respective ends of the chair 4 are provided laterally projecting perforated ears 7 adapted to accommodate securing screws or bolts 8 whereby said chair is rigidly secured to the ties 9. The rail 2 is rigidly secured to the corresponding end of chair 4 by means of bolts 10 and cooperating nuts 11, said bolts 10 passing through transversely extending openings provided in said rail and registering openings provided in the side 6 of the chair as clearly shown in Fig. 2. The rail 1 is connected with the opposite end of chair 4 by means of a vertically extending key 12 which passes through alining openings provided in the base of said chair, engaging also with a slot or notch 13 provided in the corresponding edge of the base of said rail, as clearly shown in Figs. 3 and 4. A split or cotter pin 14 cooperates with said key to releasably lock the same in operative position, said pin being adapted to releasably engage a slot 15 provided in the lower end of said key as shown. The slot 13 is of a length greater than the corresponding dimension of the key 12 in order to permit of limited relative longitudinal movement of the rail 1 and allow for expansion or contraction of the same during changes in temperature, it being known that in cold weather the rails contract and in warm weather the same expand. This expansion and contraction must be compensated for otherwise buckling of the rails or spreading of the joints results which not infrequently leads to disaster.

With the present arrangement this expansion and contraction in the rails is permitted while at the same time the rails are securely fastened together and held in alinement.

While I have illustrated and described the 110 preferred form of construction for carrying my invention into effect, this is capable of

variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters 10 Patent is:

1. In a rail joint, the combination of a pair of abutting rails; a chair in which said rail ends are mounted; a rigid connection between one of said rails and one end of said chair; a connection between the other of said rails and the other end of said chair permitting of limited relative longitudinal movement of said parts, said last mentioned connection comprising a vertically extending key removably inserted in the base portion of said chair engaging a slot provided in one edge of the base of said rail end, said slot being of a length greater than the corresponding dimension of said key; and a 25 cotter pin through said key locking the latter in said chair, substantially as described.

2. In a rail joint, the combination of a pair of abutting rails having base flanges thereon, there being a slot in one of the flanges of one of said rails; a chair disposed under the ends of said rail and having its longitudinal edge portions extending around said flanges and upwardly on the sides of said rails, one of said edge portions reaching higher than said other edge portion; 30 bolts passing through the higher of said edge portions and one of said rails rigidly securing the latter to said chair; a key passing vertically through said chair adjacent its lower edge portion and said slot adjustably securing the rail provided with said slot to said chair; and a cotter pin locking said key in position, substantially as described.

In testimony whereof I have signed my 45 name to this specification in the presence of two subscribing witnesses.

OLOF JOHNSON.
